CLAIM

The ornamental design for a caster wheel cover pod, substantially as shown and described.

DESCRIPTION

FIG. 1 is a top, left side and front side perspective view of a caster wheel cover pod showing my new design;

FIG. 2 is a top plan view thereof;

FIG. 3 is a rear side elevational view thereof;

FIG. 4 is a left side elevational view thereof;

FIG. 5 is a front side elevational view thereof;

FIG. 6 is a bottom plan view thereof;

FIG. 7 is a right side elevational view thereof; and,

FIG. 8 is a perspective view of four castor wheel cover pods applied to a caddy frame.

The broken lines in the drawing represent environment structure only and form no part of the claimed design.
